Primary Examiner — Marianne Pandozzi(74) Attorney, Agent, or Firm — Brinks Hofer Gilson & Lione(57) CLAIM

I claim the ornamental design for a wine glass container device assembly with cover, as shown and described.

DESCRIPTION

FIG. 1 is a perspective view of a wine glass container device assembly with cover showing my new design;

FIG. 2 is a front view thereof, all sides being the same;

FIG. 3 is a top plan view thereof; and,

FIG. 4 is a bottom plan view thereof.

The broken lines in FIG. 4 are for environmental purposes only and form no part of the claimed design.
